BUTTON

Leonard P. Knarreborg, La. Canada, Calif.

Application June 24, 1949, Serial No. 101,039

3 Claims. (Cl. 24—90)

1

This invention relates to buttons and has for its object to provide a button of a type which can readily be set into position on a garment, and does not require to be sewed in place.

This application is a continuation in part of my copending application Serial No. 20,207, filed April 10, 1948.

It is a common experience for buttons to come off garments, often with great inconvenience and embarrassment. There are many situations in which the wearer of the garment cannot readily sew the button back in place; and it would be desirable to have a ready replacement button which could quickly be snapped into place.

According to my invention, I provide such a replacement button. It comprises a member with a plurality of prongs protruding from a base and adapted to pass through the garment to be buttoned, so that the prongs protrude outwardly from the garment into the button member. The button member comprises the usual head, and has a sleeve passing over the prong, and the head carries a central member having mounted on it a spring element which bears against the inner surfaces of the prongs, binding and pushing the prongs against the sleeve. To use this button, it is merely required to push the prongs through the material and then snap the button member into place.

The foregoing and other features and advantages of my novel invention will be better understood from the following detailed description and the accompanying drawing of which:

Fig. 1 is an enlarged side elevation view in cross-section showing the attachment of a button according to my invention;

Fig. 2 is a cross-section view taken at line 2—2 of Fig. 1;

Fig. 3 is a side elevation view showing a detail of the construction of Figs. 1 and 2;

Fig. 4 is a side elevation view showing another detail used in Figs. 1 and 2;

Fig. 5 is a cross-section view taken at line 5—5 of Fig. 6 showing a modified form of button arrangement according to my invention; and

Fig. 6 is a plan view of the button of Fig. 5.

The button illustrated in Figs. 1 to 4 comprises a base portion 1 and the exposed button portion 2. The base member 1 is illustrated separately in Fig. 3, and comprises a flat base 3 from which protrude a number of prongs 4. The particular number of prongs shown in the embodiment in the drawing is four, but it will be understood that some other number of prongs

may be used instead if desired. Each prong protrudes substantially perpendicular from the base portion 3 and tapers to a point 5. The purpose of these pointed prongs is illustrated in Fig. 1, which shows the base member 1 in position with the base portion 3 back of a garment or fabric 6 on which the button is to be placed, and with the prong 4 stuck through the fabric and pointing outwardly.

10 The exposed button member 2 comprises a cylindrical shank 7 open at the inner end 8 and flaring outwardly at the outer end to form an annulus 9; and a disc-like head 10 is placed over the top of the button and crimped at 11 around the edge of the annulus 9. A thin flat arm or plate 12 is set within the member 2 so that it lies in a plane passing through the longitudinal axis of the cylindrical portion 7. This is done by forming the top of the plate 12 with a pair of 15 ears 13 and 14 shaped and dimensioned to fit between the cylindrical top 10 and the curved portion of the annulus 9. The plate 12 is shaped and dimensioned so that it fits snugly within the cylindrical shank 7 as shown in Fig. 2. The lower 20 end of plate 12 is provided with a pair of opposite ears 15 and 16 which are crimped around a circular disc of spring, such as spring steel 17, as shown in Fig. 4; and the diameter of spring disc 17 is slightly greater than the normal diameter 25 between opposite prongs of the base member 1.

To set the button in position on a garment, the base member 1 is pushed through the garment or material from the back or under side, leaving the prongs 4 protruding outwardly. Then the outer button member 2 is set on the prongs by placing the cylindrical portion 7 around the prongs and sliding it down over the prongs with the plate 12 between prongs as shown in 30 Fig. 2. In this position, the button member is slid down on the prongs as far as it will go, ordinarily until the base 8 of the cylindrical portion 7 is pressed against the outer surface of the fabric. While the button member is thus being pushed on the prongs, the circular spring disc 17 will be bent as it passes down inwardly between the prongs, inasmuch as its diameter is greater than the distance across opposite prongs. This will bend to press the prongs outwardly 35 against the sleeve 7. The edge of the spring disc will then engage the inner surfaces of the prongs so that the button member 2 cannot readily be pulled off the prongs. Preferably, the spring member is provided with a sharp or square 40 peripheral edge so that the corner of the square

will engage the prong members. If desired, the inner surfaces of the prongs may be roughened or serrated somewhat to provide a good engaging surface for the spring.

Figs. 5 and 6 show a modified form of button arrangement according to my invention; the principal difference from the arrangement of Figs. 1 to 4 residing in a difference in the button and spring arrangement. It will be recognized that the base member 1, with its prongs is substantially the same in Fig. 5 as in Fig. 1. The button member 2 in Fig. 5, instead of having the flat top 10 shown in Fig. 1, is formed of a disc 18 provided with a central depending conical formation 19 which may conveniently be formed or extruded from the flat disc to taper down centrally toward the base of the base member 1. Near the bottom of the cone 19, there is left a small opening or hole 20 by the turning over or crimping of the lower conical portion to form the annular flange 21. Within the annular recess formed at the opening 20 by the flange 21, there is placed the circular spring member 22, which is provided with a suitable central hole to fit within flange 21 and around opening 20. Thus, with the spring 22 in position, the flange 21 will be crimped against the portion of the cone 23 which is above the spring. The button member in Fig. 5 comprises a cylindrical shank portion 24 corresponding to the shank 7 of Fig. 1; and above cylindrical portion 24 it flares outward at 25 to meet the rim of member 18, the periphery of which is crimped at 26 around member 25. The prongs of the bottom portion 1 are forced by the spring 22 against cylindrical portion 24.

It will be recognized that the button construction of Figs. 5 and 6 embodies the same elements as in Figs. 1 to 4 insofar as the operation is concerned, but the arrangement of Figs. 5 and 6 may find a preference in view of the ease and cheapness of constructing the button head member 18 of a single sheet of material, and the simple manner by which the spring element 22 is centrally held at the bottom of the conical member 19.

It will be recognized that my invention provides a simple fastening arrangement for the button, and not only can it be easily assembled, but it will be positively held in position against pulling off.

It should also be recognized that modifications may be made in the construction within the scope of the invention. For example, it may not always be necessary, although it will usually be very desirable to provide the oblique surfaces 5a for the prongs; as the provision of such oblique surfaces at the prongs, slanting obliquely inwardly is likely to facilitate the assembly of the button by making it easier to slip the sleeve over the prongs.

10 It is understood that the invention is not limited to the particular construction illustrated in the drawing, which is given by way of illustration rather than of limitation, and that the invention is not limited except in accordance with 15 the scope of the appended claims.

I claim:

1. A button comprising a base, a plurality of prongs protruding from the base and adapted to be stuck through a fabric, an exposed head member 20 separate from the base, said head member comprising an annular disc member with a conical portion concentrically within, and extending from, the annulus and converging to smaller cross sections away from the annulus, and a disc-like 25 spring member held at the smaller end of the cone, a shank held at the periphery of the annulus and fitted over the outsides of the prongs, with the spring in engagement with the insides of the prongs, to bind the prongs against the shank.

2. A button according to claim 1 in which the disc-like spring member has a central opening which is placed over the small end of the cone.

3. A button according to claim 1 in which the small end of the cone is crimped against the disc 35 to hold the disc in place.
